A. J. E. MUNTERS.

MEANS FOR CONTROLLING THE PROPORTION OF LIQUIDS SEPARATED IN CENTRIFUGAL SEPARATORS.

APPLICATION FILED DEC. 21, 1918.

1,331,779.

Patented Feb. 24, 1920.

INVENTOR:

Anders Johan Ericsson Munters
By Mrs Wallace White

ATTY.

UNITED STATES PATENT OFFICE.

ANDERS JOHAN ERICSSON MUNTERS, OF STOCKHOLM, SWEDEN, ASSIGNOR TO
AKTIEBOLAGET PUMP-SEPARATOR, OF STOCKHOLM, SWEDEN, A CORPORATION OF SWEDEN.

MEANS FOR CONTROLLING THE PROPORTION OF LIQUIDS SEPARATED IN CENTRIFUGAL SEPARATORS.

1,331,779.

Specification of Letters Patent. Patented Feb. 24, 1920.

Application filed December 21, 1918. Serial No. 267,878.

To all whom it may concern:

Be it known that I, ANDERS JOHAN ERICSSON MUNTERS, a subject of the King of Sweden, and resident of Luntmakaregatan 57, Stockholm, in the Kingdom of Sweden, have invented certain new and useful Improvements in Means for Controlling the Proportion of Liquids Separated in Centrifugal Separators, of which the following 10 is a specification, reference being had therein to the accompanying drawing.

This invention relates to means for controlling the proportion of the liquids separated in centrifugal separators for instance 15 the proportion of skim-milk and cream in cream separators. The said means consist of a ring or the like which is rotatably mounted on the outside of the neck of the drum and when shifted reduces more or less 20 an outlet slot for one of the liquids (the skim-milk) provided in the said neck.

In the accompanying drawing Figure 1 is a side view of a separator drum provided with a controlling device arranged in accordance with this invention. Fig. 2 is a vertical section of the drum and the said device. Fig. 3 is a section on the line A—B of Fig. 2. Fig. 4 is a detail view of the controlling ring.

1 is the centrifugal drum and 2 is the top disk. The neck of the said disk extends upward into the neck 4 of the drum. The top part of the neck 4 is somewhat narrower inside than the bottom part and fits closely to 35 the neck 3. Between the bottom parts of the necks there is a passage 5. In the lower edge of the narrower top part of the neck of the drum a recess 6 is provided, which extends for some distance around the said 40 part and leads to a peripheral slot 7 provided in the neck of the drum and having substantially the same length as the recess 6. Outside the neck of the drum a ring 8 is rotatably mounted, provided with a peripheral recess 9, extending only along a part of the periphery of the ring and located outside the slot 7 in the neck of the drum. 45 10 is the ordinary central tube or the inlet tube for the full milk. 11 is a projection 50 on the neck 3, which extends through a recess provided in the neck of the drum and fitting closely to its edges. The said projection 11 extends for a distance below the

ring 8 and is provided with an outlet opening 12 for the cream.

During the operation of the centrifugal drum the separated skim-milk passes upward through the channel 5 and leaves the drum through the slot 7, while the cream passes upward through the space between the neck 3 of the top plate and the central tube 10 and leaves the separator through the opening 12. In rotating the ring 8 it is caused to cover the slot 7 more or less and thus to shut off the outlet for the skim-milk to a greater or less extent. The proportion of the skim-milk and the cream is hereby controlled, *i. e.* their percentage of fat. A dial 13 is provided on the neck of the drum, for guidance in the adjusting of the ring 8. 60 For the locking of the ring in adjusted position a screw 14 is in screw-threaded engagement with the ring and engages a groove 15 extending around the neck of the drum, so that the screw, when screwed outward for a slight distance, still engages the neck of the drum and prevents the ring from being moved axially.

Owing to the fact that the control ring, as according to this invention, is located on the outside of the neck of the drum, the manufacture of the controlling device is considerably simple and besides the ring can easily be shifted when necessary. Instead of the ring 8 any other suitable part, rotatably mounted on the neck of the drum may be used for reducing the slot 7. A plurality of slots for the skim-milk may evidently be provided in the neck of the drum a corresponding number of recesses being provided in the control ring.

Having now described my invention, what I claim as new and desire to secure by Letters Patent is:

1. In a centrifugal liquid separator, the combination of a centrifugal drum, an inwardly extending shoulder formed on the drum, the inner periphery of said drum being recessed to provide an outlet opening, a neck formed on said shoulder having an opening therein, a top disk within the drum and having a neck within the first mentioned neck and spanning the opening therein, a projection formed on the neck of the top disk and having an outlet opening therein, and a ring surrounding said necks and pro-

jection, said ring being rotatable upon said shoulder and having a recess formed in its under side and coacting with the recess in said shoulder to control the size of the opening in accordance with the position of the ring.

2. In a centrifugal liquid separator the combination with a centrifugal drum having an outlet opening in the neck thereof, of a ring-shaped member rotatably mounted on the outer side of said neck and so arranged that by shifting the ring peripherally the said outlet opening is reduced peripherally to a greater or less extent.

3. In a centrifugal liquid separator the combination with a centrifugal drum having an outlet slot in the neck thereof of a ring-shaped member rotatably mounted on the

outer side of said neck and provided with a peripheral recess coöoperating with the said slot.

4. In a centrifugal liquid separator, the combination with a centrifugal drum having an outlet opening in the neck thereof, said neck being provided with a groove, of a ring 25 rotatably mounted on the outer side of the said neck and so arranged that by shifting the ring peripherally the said opening is reduced peripherally to a greater or less extent, and a screw in said ring adapted to engage said groove thereby to lock the ring in said neck.

In witness whereof I have hereunto signed my name.

ANDERS JOHAN ERICSSON MUNTERS.
